UNITED STATES PATENT OFFICE.

HARRY D. RINDSBERG, OF CINCINNATI, OHIO, ASSIGNOR TO HARRY J. HATER, OF CINCINNATI, OHIO.

MOLD.

Original application filed April 2, 1926, Serial No. 99,407. Divided and this application filed September 14, 1927. Serial No. 219,520.

My invention relates to improvements in molds, and more particularly to the type of mold shown in my co-pending application, Serial No. 99,407, filed April 2, 1926, of which this application is a division, although applicable to other types of molds.

An important object of my invention is the provision, in a device of this character, of improved means for removing the core sections.

Another object of my invention is to provide an adjustable core supporting rack.

Other objects and advantages of my invention will be apparent during the course of the following description.

In the accompanying drawings which form a part of this specification and wherein like characters of reference denote like or corresponding parts throughout the same,

20 Figure 1 is a side elevation of my improved mold,

Figure 2 is a similar view showing the mold sections separated and the cores withdrawn, and,

25 Figure 3 is a detail perspective view of the balance arm swiveling member.

I have selected for the purpose of illustration, a "one man mold" of the type shown in my co-pending application above referred to, although the present invention is by no means limited to a mold of this type.

In the drawings wherein for the purpose of illustration is shown a preferred embodiment of my invention, the numeral 1 designates a suitable base plate on which a pair of mold sections 2 and 3 are mounted as is usual, the mold cavity being arranged in the meeting faces of the sections 1 and 2 as is also usual.

40 The construction and operation of this type of mold is fully described in the application of which this is a division and therefore does not require detailed description here. The core members are of the usual

45 construction and comprise a central core member 7 flanked by exterior core members 8, the core 7 having an upstanding rod 9 by which it may be manipulated, the other core members having handles 10 extending in the same general direction.

In order to facilitate the work of the single operator of this machine of the "one man type", and to avoid possible damage to the core members, I provide a special holder

to receive these core members when they are removed from the mold cavity. This holder comprises a pair of upstanding arms or side members 57 secured to a mold support 85. To the upper ends of the side members 57, a pair of inclined pans or trays 58 and 59 are 60 adjustably secured by means of integral brackets or lugs 58^a and 59^a held in place by bolts 59^b which fit in openings 59^c, there being a sufficient number of openings to allow of a large range of adjustment. Each 65 of these pans or trays may conveniently be made of cast iron or the like but are provided with a lining 60 of sheet brass or other relatively soft metal so as to prevent damage to the core members when the same are placed 70 therein.

Segment plates 61 are interposed between the mold support and the arms 57, the arms 57 being adjustably secured thereto by means of pivot bolts 62 arranged at the lower ends 75 of the segment plates and adjusting bolts 63 extending through arcuate slots 64 in the plates 61. It will be seen that not only may the trays be adjusted for different workmen, but the supporting arms 57 are capable of a 80 large range of adjustment by moving the adjusting bolts 63 in the slots 64. In this way different sizes of workmen may be readily accommodated.

Arranged at the upper end of one of the 85 arms 57 is a swivel connection comprising a body portion 65 bolted to the arm 57 and having a vertical bore in its upper end for the reception of a swivel pin 66 carried by a forked swivel 67. The crotch of the fork 90 is substantially inverted V-shape in cross-section as shown at 68 in dotted lines in Figure 1.

A balance arm 69 is pivotally connected between the arms of the fork at 70 and rests 95 upon the apex of the V at 68. It will be seen that the balance arm is capable of swiveling about an angle of 360 degrees and is also capable of pivoting about the connection 70 by reason of the V-shaped portion 68.

One end of the balance is provided with a weight 71 adjustably clamped to the arm by means of the bolt 72. The other end of the balance is provided with a chain 73 or similar device provided at its lower end with a suitable connection 74 for detachably engaging the arm 9 of the center core section 7. It will be seen that when the core sections are

to be removed, the balance arm can be drawn down and the chain connection 74 attached to the handle 9 of the core section 7 and that the weight 71 will withdraw the core section 5 as shown in Figure 2. The balance can then be swung out of the way and the remaining core sections can be readily removed and placed in the trays. It is to be understood, however, that the balance may be used on 10 molds having any number of core sections.

While I have shown and described the preferred embodiment of my invention it is to be understood that various changes in the size, shape, and arrangement of parts may be 15 resorted to without departing from the spirit of my invention or the scope of the subjoined claims.

Having thus described my invention, what I claim and desire to protect by Letters Patent is:

1. In a device of the character described, a mold having a core member, a supporting arm secured adjacent to said mold, and a weighted pivoted balance arm swiveled to 25 said supporting arm and having means on one end for detachable connection with the core member, whereby the weighted balance arm will withdraw the core member from the mold.
2. In a device of the character described, a mold having a removable core member, and a core drawing apparatus comprising a swivel connection arranged above said mold, a balance arm pivotally secured to said 35 swivel connection, a weight arranged on one end of the balance arm, and a member flexibly secured to the other end of the balance arm

and adapted for detachable connection with the core member, whereby the weight will pivot the balance arm to withdraw the core 40 member.

3. A mold core supporting and drawing apparatus comprising a mold having a frame and a mold section having a cavity open at the top, a plurality of core members adapted 45 to fit within said cavity, a supporting rack, a pivoted balance arm swiveled to the rack and having a weight on one end and a member on the other end adapted for detachable connection with one of the core members whereby 50 the weight will pivot the balance arm to withdraw the core member, and a tray on said rack adapted to receive the other core members.

4. The combination with a molding machine comprising a frame, a support therefor and a pair of separable mold sections mounted thereon, each containing complementary parts of the mold cavity, said cavity being open at the top, of a plurality of core members adapted to fit within said cavity, a supporting rack carried by the mold support, said rack being adjustably connected to the support, a swivel carried by the rack, a balance arm pivotally secured to the swivel, a 65 weight on one end of the balance arm, and a member flexibly connected to the other end of the arm and adapted for detachable connection with one of the core members to withdraw the same from the mold cavity, and a 70 tray carried by the rack to receive the other core members.

In testimony whereof I affix my signature.

HARRY D. RINDSBERG.
